HOLDER FOR A COMBINED SAFETY RAZOR AND MOUNT

Irving Harper, Rye, N.Y., assignor to Wilkinson Sword
Limited, London, England, a British company

Filed Oct. 16, 1968, Ser. No. 14,022

Claims priority, application Great Britain Apr. 24, 1968

Term of patent 14 years

Int. Cl. D28—03

U.S. Cl. D95—3

FIG. 1.

FIG. 2.

FIG. 3.

FIG. 4.

FIG. 5.

I claim:

The ornamental design for a holder for a combined safety razor blade and mount, as shown and described.
